APPARATUS FOR REATOMIZING FUEL.

Application filed February 23, 1922. Serial No. 538,740.

This invention relates to an apparatus for reatomizing hydrocarbon fuel, and is particularly directed to such apparatus as applied to internal combustion engines.

It is well known that in the ordinary operation of an apparatus using a hydrocarbon fuel, such apparatus, for example, being an internal combustion engine, that condensation of the fuel, in the conducting portion 10 of the system between the carbureting device and the apparatus utilizing such fuel, frequently occurs. This is particularly true with an internal combustion engine as the frequent starting and stopping and also the varying speed of the engine allows a temporarily unused charge to accumulate in the intake manifold, or to temporarily remain at rest in such manifold. Condensation, therefore, naturally follows. Also, in the 20 normal operation of the engine, the intake manifold may be at such a temperature as to allow a gradual condensation to continuously occur.

It is therefore an object of this invention 25 to provide a method for overcoming the above enumerated defects and provide for the reatomizing of the condensed fuel.

Further objects are to provide an apparatus for collecting and reatomizing the condensed fuel; to provide an apparatus which will operate as a temporary storage reservoir for the condensed fuel; which will prevent circulation of air when the engine is still, thereby minimizing unwanted evaporation of the fuel; and which gives a rich mixture on starting and thereby automatically primes the engine when starting.

Further objects are to provide a reatomizing apparatus which may act either continuously to reatomize the continuously condensed fuel; or may act intermittently to reatomize the intermittently condensed fuel; as for example when the engine is stopped and started.

Further objects are to provide an apparatus for internal combustion engines which will aid in starting the motor by providing a very rich mixture at starting; which gradually varies this rich mixture until it assumes its normal proportions without any sudden change in which provision is made for varying the temperature of the air used in reatomization; and in which improved economy is attained.

Embodiments of the invention are shown in the accompanying drawings, in which:

Fig. 1 is a side elevation of a portion of an internal combustion engine and intake manifold with the device in position upon the latter.

Fig. 2 is an enlarged view of the device partly in section.

Fig. 3 shows a modified form of construction.

Figs. 4, 5 and 6 show details of modified forms.

Fig. 7 is a view corresponding to Fig. 1 showing a further modified form of the invention.

Fig. 8 is an enlarged detail of the apparatus detached from the intake manifold.

Fig. 9 is a view corresponding to Fig. 8 and taken at right angles to such figure, showing the bottom cap removed.

The method contemplated by this invention comprises collecting the condensed fuel and reatomizing this condensed fuel by admitting atmospheric air adjacent such collected fuel. It contemplates both the continuous collecting of the continuously condensed fuel, and both the intermittent storing or collecting of relatively larger quantities of fuel following a stopping of the engine with the subsequent reatomization thereof at the starting of the engine, thereby overcoming the necessity for priming in the latter case, and providing a more efficient method of utilizing hydrocarbon fuel in the former case. It contemplates further the varying of the temperature of the incoming air used for reatomization and the gradual changing in the richness of the mixture during the period from starting to the period of normal operation—that is to say, the method contemplates supplying the motor with a very rich mixture at starting and gradually thinning this mixture automatically as the engine warms up, so that there is no sharp or sudden change in richness of mixture from starting to normal running.

The construction in Figs. 1 and 2 will first be described. The internal combustion engine 1 is equipped with the usual manifold 2 and with a carburetor 3. Between the portion of the intake manifold adjacent the carburetor and the portion adjacent the engine, a union, such for example as flanges 4 and 5, are customarily provided and are adapted to be bolted together to secure the continuity of the intake manifold. The device is adapted to be positioned between these flanges and to be bolted in such loca-

tion. It comprises a member 6 corresponding in outline roughly to the flanges 4 and 5 and having an opening 7 corresponding to the interior opening or passage of the manifold, and with a pair of openings 8 in alignment with the usual bolt hole openings in the flanges 4 and 5. The faces of the member 6 are adapted to either contact with the faces of the flanges 4 and 5 to secure a tight joint, or are adapted to be supplemented by a gasket in the usual manner. This device has a recessed portion or pocket 9 in direct communication with the opening 7 and is provided with a tube 10 extending through the bottom portion 11 of the pocket 9 and projecting both above and below such bottom portion. This tube has a contracted portion 12 formed therein at a point above the bottom portion 11 of the pocket to form in effect a Venturi tube or constricted opening placing the storage reservoir 14 in communication with the manifold. A series of openings 13 are formed in the tube, and place either the throat, or a portion adjacent the throat of the tube in communication with the exterior. The lower portion of the re-atomizing device is provided with a relatively large receptacle or storage reservoir 14 formed by converging walls 15 and a bottom portion 16. This chamber is placed in communication with the outside air by means of a port 17 which may conveniently be formed at the side of the main member and beyond the outline of the flanges. It will be observed therefore that in the embodiment of the invention shown in Figs. 1 and 2, the tube or constricted opening, reservoir and port, comprise for air a passage leading from the exterior to the interior of the manifold.

The operation of the device is as follows: While the engine is continuously running, it is obvious that under certain conditions of temperature of the intake manifold, and frequently under all conditions of certain types of engines, condensation of the fuel occurs. This condensed fuel frequently runs out of the air inlet of the carburetor and sometimes runs out of an auxiliary drain frequently provided with certain types of carburetors. This apparatus, however, allows the collecting of the condensed fuel within the pocket, or smaller reservoir 9, in the normal operation of the engine, and this collected fuel is then reatomized through the instrumentality of the Venturi tube 10. Air is drawn through the opening or port 17 and through the tube 10, and it is at once apparent from an inspection of Fig. 2 that the pressure in the throat portion of the tube is below that in the pocket 9 and fuel is therefore drawn into this rapidly passing stream of air and atomized. This, it will be seen, provides a continuous reatomization of the condensed fuel and therefore mate-

rially increases the efficiency of the entire system. However, it is also desirable to provide a richer mixture at starting than under normal conditions so as to avoid the necessity of priming. This is readily secured by this device, as the condensed fuel fills the pocket 9 and overflows into the reservoir, or pocket 14, by passing into the openings 13 and downwardly through the tube 10 when the engine is stopped. This quantity of fuel is relatively greater than that normally held in the pocket 9, as the entire charge is brought to rest within the intake manifold when the engine stops, and condensation of larger quantities necessarily follows. It will be seen that the device prevents unwanted circulation of air with consequent disadvantageous evaporation when the engine is still, as it forms both a constricted passageway and also, in effect, a trap as the fuel seals the lower end of the tube 10. However, when the engine is again started, the fuel is drawn upwardly through the pipe 10 and fills the pocket 9 and, under certain conditions, adjacent portions of the manifold. It is, however, rapidly sucked into the tube 10 and intimately mixed with this flowing stream of air and therefore reatomized. It is, therefore apparent, that on starting, a relatively rich mixture is automatically supplied the engine without requiring any attention of the operator.

It may be found desirable under certain conditions, to provide means for attaching the device to an intake manifold which may not conveniently be separated in the manner previously described. This is readily secured by providing a device such as that shown in Figs. 3 and 4. This device comprises a tubular body 18 provided with a storage cavity 19 and with a smaller storage cavity or pocket 20. It is similarly equipped with a Venturi tube 21 provided with a throat and with orifices 22 as previously described. The storage cavity 19 is provided with a duct 23 placing it in communication with the exterior. The upper portion of this device has a reduced threaded neck 24 adapted to be screwed into a tapped hole 25 in the intake manifold 26. It is thus seen that all that is necessary to adapt the intake manifold for the reception of this device is to drill and tap a suitable hole therein. This type of device operates in a manner substantially similar to that previously described. It, however, may be placed either in the position shown at the lower portion of Fig. 3 or if desired in the positions shown in the upper portion of Fig. 3, that is, it may be secured to the relatively horizontal portion 27 of the manifold. This may become desirable in the case of a vertical manifold neck.

A further form of the apparatus is shown in Fig. 5 and it will be seen that the tubular member 28 is not provided with a Venturi

tube, but is provided with an air tube 29 communicating with the outside air and extending downwardly through the collected or stored fuel 30 as illustrated in the figure, 5 thereby causing the air to bubble up through the fuel and provide a rich reatomized mixture. Also, it will be noted that in the continuous operation of the device, the pocket 31 may be partially filled with fuel and air may 10 be continuously drawn through the fuel while it is within this pocket.

A further form, shown in Fig. 6, comprises a tubular storage member 32 within which the gasoline may accumulate. The pocket 15 or smaller storage cavity 33 is provided with an integrally formed downwardly extending tube 34 which extends to a point adjacent the bottom portion of the member 32. An air inlet or port 35 is provided in the upper 20 portion of the tubular member. When the engine is stopped, a relatively large quantity of fuel may collect within the member 32, and upon restarting is drawn upwardly through the tube 34, thereby filling the pocket 33 and, under certain conditions, adjacent portions of the manifold. Air is drawn through the tube 34, after this discharge of fuel, and passes through and re-atomizes the elevated fuel. During the continuous 25 operation of the device, the continuously condensed fuel may collect within the pocket 33 and air may be drawn continuously through this collected fuel.

Fig. 7 shows the preferred form of the invention, and it is to be noted that the re-atomizing device comprises a cylindrical open bottom member 36 having an upper portion 37 provided with a central passage-way 38 and with bolt holes 39, such upper member being adapted for positioning between the flanges 40 and 41 of the intake manifold in a manner similar to that described in connection with Figs. 1 and 2. The cylindrical member 36 is provided with an inner cavity 42 and with a flanged bottom portion 43 provided with a circular recess 44. A stamped cap 45 is adapted to be seated, as shown in Fig. 8, within this circular recess and to be soldered, brazed, welded, or otherwise secured in position, thereby sealing the bottom portion of the device and providing a relatively constricted lower pocket 46 or receptacle 45. The cavity 42 is placed in communication with the outside air by means 55 of a port 47 formed in an upstanding outwardly slanting arm 48 cast integrally with the main portion of the apparatus and preferably joining the upper portion 37 and the lower portion 36, as shown in Fig. 8. This arrangement facilitates drilling or otherwise forming the port 47 and also facilitates any work that is necessary within the cavity 42 as the bottom 45 is placed in position only as a final operation.

65 A tube 49 extends through the neck portion

50 of the apparatus and down into close proximity to the bottom portion of the well or pocket 46. Its lower end is beveled as indicated at 51 so as to provide adequate entrance area for the air passing into the 70 lower end of the tube and yet to provide a tube with an extension closely approaching the bottom of the well 46. This construction utilizes capillary action as it is well known that the gasoline will wet the surface of the tube as long as one of its edges projects into the liquid. In this manner, it is possible to withdraw from the cavity or pocket 46 practically the last drop of gasoline that may have accumulated therein. 75 The upper portion 52 of the tube 49 is bent or curved in the direction of the incoming charge. This further enhances the suction produced in the tube 49 in a well known manner. At a point between the upper and lower portion of the tube and preferably at the upper portion of the neck 50 of the apparatus, the tube is constricted as indicated at 53 so as to provide a Venturi tube or constricted opening placing the manifold and receptacle in communication. An aperture 54 is formed in the wall of the tube immediately above the constricted or throat portion and this aperture places the interior of the tube at this point in communication with the lower portion of the intake manifold. The tube 49 is provided with a series of spaced apertures 55, 56, and 57.

In place of forming a temporary collecting reservoir or cavity such as indicated at 9 in Fig. 2, a dam 59 is formed across the hole 38 in the upper portion 37, the relative size or height of the dam to the diameter of the opening being preferably that as shown in Fig. 8. This dam, it will be seen, prevents condensed fuel from passing outwardly along the intake manifold and causes it to become stored upon the forward side of the dam, that is to say, nearest the engine. This collected fuel, in the normal operation of the engine, is sucked through the opening 54 in the tube and is atomized by the upwardly passing air and is again discharged through the curved portion 52 of the tube in a reatomized state.

When the engine is stopped, the condensed fuel which is normally passing into the tube 49 through the opening 54, as well as the fuel condensed from the unused charge standing in the intake manifold, flows down the tube 49 and collects within the cavity 42. It is to be noted that when the engine is again started, air may pass through the upper portion of the slit, if such is formed in the tube 49. In this manner, a relatively small amount of air is mixed with the fuel drawn upwardly through the tube 49 and a very rich mixture is presented to the starting engine. As the engine warms up, or attains

speed, and as the fuel trapped within the cavity 42 is gradually used, its level becomes lower and lower and more air in proportion to the fuel passes into the tube 49 as more openings are uncovered by the gradually receding fuel. The last portion, practically, of the trapped gasoline may be drawn upwardly through the tube as previously described in connection with the slanting bottom 51. It will be seen, therefore, that a very gradual change is secured between the extremely rich mixture furnished at starting and the normally less rich mixture used in the usual running condition of the engine.

As has been noted with reference to Figs. 1 and 2, it will also be noted that in the embodiment shown in Figs. 7 to 9 inclusive, the constricted opening formed by tube 49, the reservoir 45 and the port 47 formed for air a passage leading from the exterior to the interior of the manifold.

If it is desired, a tube 60 may be wrapped around the exhaust manifold 61 and may have its end 62 bent downwardly and adapted for temporary connection with the port 47, as for example, by slipping the end of the tube within such port. The tube 60 is loosely wrapped about the manifold and therefore permits relative motion between such tube and the reatomizing device. If it is desired, the tube 60 may communicate with other portions of the motor, or may communicate either directly or indirectly with the radiator and thereby draws heated, moist air into the reatomizing apparatus.

It will be found that increased economy is secured by the use of this apparatus as a more uniform mixture of fuel and air is presented to the engine, that is to say, as the fuel and air are more intimately mixed than heretofore. It will also be seen that in extremely cold weather, or whenever otherwise demanded, heated air may be used for the reatomization.

The dam 59 also serves to direct the incoming air and fuel upwardly to a slight extent to thereby avoid any interference with the rearwardly flowing condensed fuel. It will be seen therefore, that the rearwardly flowing fuel lying against the bottom inner surface of the intake manifold, may freely flow until stopped by the dam 59. A further effect of this dam is that it aids in the production of suction within the tube 49 in a well known manner.

It will thus be seen that a method and apparatus have been provided for reatomizing condensed fuel and automatically providing a richer mixture at starting thereby avoiding the necessity for priming. It will also be seen that a relatively simple device having no moving parts, or parts likely to be worn, has been provided and that this device

may be both cheaply manufactured and easily applied.

I claim:

1. In a fuel re-atomizing device adapted to be associated with the intake manifold of an internal combustion engine, a device comprising a reservoir having a constricted opening for communicating with the manifold and having also a port for communication with the exterior of said reservoir, and means for directing fuel condensed in the manifold into said reservoir, said opening, reservoir and port comprising a passage leading from the exterior of the manifold to the interior thereof.

2. In a fuel re-atomizing device, a reservoir having means for attachment thereof to the intake manifold of internal combustion engines and provided with a constricted opening for communication with the manifold and a port for communication with the exterior of said reservoir, and means for directing fuel condensed in the manifold into said constricted opening, said constricted opening being adapted to pass said fuel into said reservoir, said opening, reservoir and port comprising a passage leading from the exterior of the manifold to the interior thereof.

3. In a fuel re-atomizing device adapted to be associated with the intake manifold of an internal combustion engine, a device comprising a perforated member adapted to form a continuation of the manifold and having a dam formed therein, and partially closing said perforated portion, a reservoir placed below such dam, means for directing condensed fuel into said reservoir, said means including a tube extending downwardly into said reservoir and bent in the direction of flow of the incoming air through said intake manifold, said tube having a series of apertures arranged in spaced relation and in communication with the interior of said reservoir and having a lower beveled end.

4. In a fuel re-atomizing device adapted to be associated with the intake manifold of an internal combustion engine, a device comprising a member having a cavity, an apertured portion on said member adapted to constitute a part of the manifold and having a hole affording communication between said aperture and cavity, a receptacle adapted to be attached to the bottom of said member and to close the cavity, a tube extending through the hole and into the receptacle and communicating with the manifold, and an air intake adapted to direct air from the exterior of said member to the cavity thereof.

5. A re-atomizing device comprising a manifold section having a passage leading into said section from the atmosphere, said passage including a reservoir below said sec-

tion, a port for communication with the exterior of said reservoir and vertically spaced above the bottom of said reservoir, and a fuel inlet and outlet duct leading from the 5 lower portion of said reservoir to the interior of said section; said duct comprising the only means of fuel access to said reservoir; whereby fuel entering said passage from said manifold will encounter air admitted 10 through said passage and fuel accumulating in said reservoir will be elevated to said manifold.

6. A fuel re-atomizing device comprising a manifold section having a dam extending 15 across said section, a reservoir depending from said manifold section and provided with an opening affording communication with the atmosphere, a tube extending from a position above said dam and into said 20 reservoir, said tube being adjacent said dam and provided with a fuel inlet hole adjacent the manifold section and below the upper margin of said dam.

7. In a fuel re-atomizing device adapted 25 to be associated with the intake manifold of an internal combustion engine, a device comprising a receptacle adapted to be secured to the manifold, a tubular member extending

into the receptacle and adapted to extend 30 into the manifold, said tubular member having a constricted area and provided with a hole adapted to be positioned adjacent the periphery of the inner wall of the manifold, and a dam adapted to direct condensed fuel 35 into the hole in said tubular member.

8. A fuel re-atomizing device comprising a manifold section having a dam extending across said section, a reservoir depending from said manifold section and provided with an opening affording communication 40 with the atmosphere, and a tube extending from a position above said dam and into said reservoir, said tube having a constricted portion below said dam and a fuel inlet hole above said portion and adjacent said 45 section.

9. In a re-atomizing attachment for intake manifolds, a manifold section, an atomizing device carried by said section and including a Venturi tube, and a reservoir provided with an air admission port, said reservoir being interposed between said Venturi tube and port and arranged to receive condensate from said manifold. 50

ELLING O. WEEKS.
